UNITED STATES PATENT OFFICE.

ARNOLD C. MESSLER, OF PAWTUCKET, RHODE ISLAND.

DESIGN FOR A BADGE.

SPECIFICATION forming part of Design No. 33,277, dated October 2, 1900.

Application filed June 11, 1900. Serial No. 20,467. Term of patent 7 years.

To all whom it may concern:

Be it known that I, ARNOLD C. MESSLER, a citizen of the United States, residing at Pawtucket, in the county of Providence and State of Rhode Island, have invented and produced a new and original Design for Badges, of which the following is a specification, reference being had to the accompanying drawings, forming part thereof.

10 Figure 1 is a front elevation of my new design. Fig. 2 is a side elevation of the same.

As shown in the drawings, my design for a badge consists of an article of manufacture of the shape or configuration of a human skeleton with the fingers distended and the limbs extending at an angle from the cen-

tral shield-shaped body portion, the outside face of which is plain. The whole is attached to a pin.

Having described my invention, what I claim as new, and desire to secure by Letters Patent, is—

The design for a badge, substantially as shown and described.

In testimony whereof I have signed my name to this specification in presence of two subscribing witnesses.

ARNOLD C. MESSLER.

Witnesses:

ALFRED S. JOHNSON,
HOWARD A. LAMPREY.
